BY HER ATTORNEY

Nelson M. Howard

UNITED STATES PATENT OFFICE

EDWARD ERICKSON, DECEASED, LATE OF BEVERLY, MASSACHUSETTS, BY MARY E. ERICKSON, EXECUTRIX, OF BEVERLY, MASSACHUSETTS, ASSIGNOR TO UNITED SHOE MACHINERY CORPORATION, OF PATERSON, NEW JERSEY, A CORPORATION OF NEW JERSEY

FLUID-APPLYING MACHINE

Application filed February 26, 1927. Serial No. 171,317.

This invention relates to fluid-applying machines for use in the manufacture of boots and shoes and is illustrated as embodied in a machine arranged to apply cement to economy insoles.

When machines used for applying fluid to various boot and shoe parts are used in connection with soles and insoles, the difficulty of handling the work without interference between the soles and parts of the machine becomes somewhat acute, especially when following around the deeply indented shank portion of some such insoles. Machines have been shown in my prior application, Serial No. 579,443, filed August 3, 1922, upon which Letters Patent of the United States No. 1,669,508 were granted May 15, 1928, and in application Serial No. 122,150, filed July 13, 1926, in which a frusto-conical applying roll is mounted upon an axis at the front of the machine inclined downwardly toward the rear, and in which fluid is supplied to this roll from a receptacle disposed to the rear thereof, said fluid being elevated from the receptacle and supplied to the applying roll at a point remote from the point of application of the work thereto.

One object of the present invention is to provide an improved machine of this general type having more room for the manipulation of pieces of work without interference with the machine.

With this in view, a feature of the invention resides in the interposition of a novel transfer means between the fluid applying member and the supplying member which dips in the receptacle, this transfer means being substantially horizontally disposed above the area provided for the manipulation of pieces of work. By reason of this construction it is possible to provide a relatively wide separation between the applying member and the fluid receptacle to allow free manipulation of the work, while maintaining a compact and efficient design. In the illustrated construction both the applying roll and the supplying roll are frusto-conical members mounted on inclined axes and arranged to cooperate with opposite sides of the interposed disk-shaped transfer roll arranged upon a

vertical axis and disposed above the area provided for the manipulation of work. The fluid receptacle is provided with a lip extending beneath the transfer means arranged to underlie the points of co-operation between the transfer means and the supplying and applying means, thereby to keep the cement from dripping on the work or the floor.

Other features of the invention reside in novel mechanism for controlling the quantity of fluid delivered to the applying roll by adjustably determining the relative approach of the respective rolls. In the illustrated construction the rolls are power-driven, and means are provided for adjusting the position of the applying roll with respect to the transfer roll without impairing the driving connection to said applying roll. As illustrated also, the applying roll and the transfer roll are mounted upon a slide normally biased to an adjustably predetermined limit in which the transfer roll is separated from the supplying device and operator-controlled means are provided for moving said slide to bring the transfer roll and the supplying device into co-operative relation.

Still another feature of the invention relates to a novel arrangement for supporting the fluid receptacle in the frame of the machine to allow its ready removal for cleaning.

One specific embodiment of the invention will now be described with reference to the accompanying drawings, in which

Fig. 1 is a side elevation of the machine with parts broken away and in section;

Fig. 2 is a longitudinal section taken through the axis of the fluid-carrying rolls and drawn on a somewhat larger scale;

Fig. 3 is a plan view of the machine with the cover removed and parts of the casing in section;

Fig. 4 is a front elevation; and

Fig. 5 is a section on the line V—V in Fig. 4 through the neck of the supply tank.

The frame 10 of the illustrated machine is provided with a socket member 12 arranged to permit the support of the machine upon the tapered upper end of a suitable pedestal 14, and an electric motor 16 is suitably supported upon the frame of the machine so that

the main shaft 18 of said machine may be driven from said motor through a suitable worm and gear speed-reduction mechanism 20.

5 The particular embodiment of the invention herein illustrated is especially designed for use in applying cement to economy insoles 22 (Fig. 2) before the lips 24 of the insole are turned and brought together. For 10 this work a solid applying roll 26 may be used, which is of frusto-conical form and is supported for rotation upon a shaft 28 the axis of which is inclined downwardly to the rear. The cement is supplied to the applying roll 26 from a receptacle 30 by a cylindrical transfer roll 32 supported for rotation with a vertical shaft 34 and a frusto-conical supplying roll 36 upon a shaft 38 the axis of which is inclined downwardly toward the 15 front of the machine. The arrangement is such that the axes of these shafts are in a common plane and intersect one another. This permits the receptacle 30 to be placed at considerable distance from the applying roll 20 25 30 35 40 45 50 55 60 65 70 75 80 85 90 95 100 105 110 115 120 125 130

26 so as to give greater freedom for the manipulation of work in contact with said roll, it being understood that cement is elevated from the receptacle by means of the supplying roll 36, and delivered from this roll to the face of the cylindrical transfer roll 32, which in turn delivers the cement to an upper point upon the applying roll 26. In order that any dripping of the fluid at the points of cooperation between said rolls may be kept from soiling the work or the floor, the receptacle 30 is provided with a forwardly extending lip 40 underlying these points but so far elevated above the plane in which the piece of work, such as the insole 22, is being manipulated that it does not interfere with said work. When the machine is used for applying cement to economy insoles, a corrugated work-supporting roll 42 may be provided rotatably mounted upon the forward end of an arm 44 pivotally secured at 46 to the receptacle 30. A spring 48 is arranged to hold the roll 42 in yielding contact with the lower face of the work, and an adjustable stop 50 is provided for limiting the upward movement of said roll so that it may not contact with the cement-applying roll 26. A U-shaped bracket 52 formed upon the under side of the lip 40 of the receptacle serves as a guide for the forward end of the arm and co-operates with the spring 48 and the stop 50. An edge gage 54 is adjustably mounted upon the forward end of the arm 44 and is positioned in a groove 55 by means of a clamp screw.

Under certain conditions and when handling certain kinds of fluid, it has been found that the quantity of fluid delivered from the receptacle to the applying roll 26 may best be controlled by adjustably determining the relative approach of the various rolls. Then,

too, it is important to be able to interrupt the supply of fluid to the applying roll when work is not being presented to the machine. Accordingly, the illustrated machine is provided with a slidable frame 60 carrying the applying roll 26, the transfer roll 32 and driving mechanism therefor. In order to support the slidable frame 60 upon the frame 10 of the machine, the slidable frame is provided with rods 62 and 64 (Fig. 3) bolted to said frame at 66 and 68 and with a cross-bar 70 bolted to said slidable frame and slidably mounted upon a rod 72 secured in a bracket 74 by means of a set screw 76 (Fig. 1). The bracket 74 is secured to the frame 10. A spring 78 (Fig. 3) is interposed between the bracket 74 and the cross-bar 70 on the slide of the frame, urging the sliding frame against a wedge-shaped limiting stop 80 interposed between a nut 82 upon the end of the rod 72 and the cross-bar 70. The position of this wedge-shaped stop may be adjustably determined by means of a spring 84 urging it in one direction and the opposing action of a hand wheel 86 threaded upon a bolt 88 attached to said stop and passing through a supporting arm 90 formed integrally with the cross-bar 70 which is secured to said slidable frame. The rods 62 and 64 secured to the rear of the frame 60 pass through bearings formed in lugs 92, 94 (Figs. 1 and 3) upon the frame 10 and are provided with spring 96 and 98, said springs bearing at one side against the lugs 92 and at the other side against stops 100 adjustably fixed upon the rods. Thus these springs assist the spring 78 in moving the sliding frame to its limiting position where the transfer roll 32 is carried out of co-operative relation to the fluid-supplying roll 36 so that no fluid is delivered to the applying roll 26. Operator-controlled means are provided including a treadle-operated rod 102 adapted to move a lever 104 which bears against one of a pair of bell crank levers 106 upon a shaft 107 and engaging stops 108 upon the extended outer ends of the rods 62 and 64. This arrangement allows the operator to bring the train of rolls into co-operative relation so that the fluid will be carried over from the receptacle 30 to the applying roll 26 when the operator is ready to present work to the machine and to interrupt this delivery of cement when the presentation of work is to be interrupted.

Provision is made for driving the various rolls in the train from the main shaft 18, and the arrangement is such that the driving connections are not impaired by the various adjustments and movements of translation already described. The supplying roll, 36, the shaft 38 of which is journaled in a part of the frame 10, is driven from the shaft 18 by means of bevel gears 110. In the sliding frame 60 a countershaft 112 (Fig. 2) is provided, and this countershaft is driven from

the main shaft 18 by means of coacting spur gears 114 and 116, it being noted that the spur gear 116 has a wider face than the gear 114 so that it will always remain in mesh with the gear 114 as the sliding frame 60 is moved. Bevel gears 118, 120, one upon the countershaft 112 and the other upon the stud shaft 34, drive the transfer roll 32.

In order that the relative approach of the applying roll 26 and the transfer roll 32 may be adjustably controlled, the shaft 28 of said applying roll and other driving connections to be described are mounted in an adjustable bracket 122 having an extension 124 which is sleeved in a bearing 126 provided upon said sliding frame 60. A stub shaft 128, journaled in the extension 124 (Fig. 2), has a pin and slot connection 130 with the end of the countershaft 112 and bevel gears 132 and 134 are pinned to the respective shafts 128 and 28 which provide a driving connection therebetween. A bolt 136 having a headed end 138 rotatably secured in the bearing 126 is threaded in the adjustable bracket 122 and may be rotated by means of a knurled head 140 and clamped in adjusted position by means of a clamp bolt 142 in the bearing bracket 122. Another clamp bolt 144 is arranged to hold the bearing 126 in its adjusted position. This arrangement provides for the adjustment of the distance between the adjacent faces of the applying roll 26 and the transfer roll 32, thereby to determine the amount of fluid carried over from one to the other.

A cover 150 secured to the bracket 74 by a bolt 151 and to the frame of the machine by a bolt 152 is arranged to conceal the operating parts and is provided, as shown in Fig. 4, with outwardly extending lips 153 having depending dowel pins 154 tapered at their lower ends. The receptacle 30 is provided with apertured lips 156 arranged to be brought up into engagement with the lower ends of these dowel pins in order to position the receptacle upon the machine, and this position may be maintained by means of a locking bolt 158 (Fig. 1) slidable in the main frame 10 and adapted to be operated by means of a gear-and-rack connection to a hand wheel 160. This arrangement facilitates the removal and replacement of the receptacle when it is desired to clean the same and insures the proper positioning of the receptacle without excessive care on the part of the operator. A supply of cement or other fluid may be contained within a tank 162, the arrangement being that of a barometric supply in which the level 164 of the fluid in the receptacle 30 is determined by the position of the outlet opening of the tank 162, and this may be varied, if desired, by adjustment of a collar 166 upon which the tank 162 is supported when it is placed in inverted position upon the receptacle 30. The difficulty of bringing an open-ended tank to inverted posi-

tion within the receptacle without spilling some of the contents thereof, especially when the tank is of any considerable size or weight, will be readily appreciated. Accordingly, means have been provided allowing the tank to be placed in inverted position directly over the receptacle before the fluid is allowed to escape therefrom. To this end a butterfly valve 168 having a projecting arm 170 is secured upon a sleeve 172 adapted to be inserted in the neck 174 of the tank 162 before the inversion of the latter, it being understood that the butterfly valve is then in closed position. The position of the sleeve 172 with respect to the neck 174 of the tank is determined by a collar 176 fixed upon said sleeve. The receptacle 30 is then provided with a slot 178 (Fig. 5) to allow the admission of the arm 170 of the butterfly valve, and as the tank is inverted and lowered into position upon the receptacle, the arm 170 may be brought into engagement with a side of the slot 178 and the tank given a partial rotation to open the butterfly valve and then dropped immediately into position.

It will be understood that the invention is not limited to an arrangement for applying cement to Economy insoles since it may, with only slight modifications, be equally well used for channel-cementing or for sole-inking. For either of these uses the work-supporting roll 42 and associated parts will be dispensed with, and when the machine is to be used for channel-cementing, a brush similar to that illustrated in the earlier application referred to above will be substituted for the solid applying roll 26. When the machine is to be user for sole-inking, either a solid roll or a brush may be used as determined by the character of the work and the nature of the ink to be applied.

The novel features of the herein-disclosed means for facilitating the positioning of an inverted supply tank upon the machine are not claimed herein since they are claimed in divisional application Serial No. 344,060 filed March 2, 1929.

Having described the invention, what is claimed as new and desired to be secured by Letters Patent of the United States is:

1. In a machine for applying fluid to a shoe part, an applying roll rotatable about an inclined axis having a lowermost face exposed for the application of work thereto, a fluid receptacle, means for taking up fluid from said receptacle and delivering it to a point upon said applying roll remote from the point of application of the work, said means comprising a member dipping in the fluid in the receptacle, and a transfer member positioned above the fluid in the receptacle and arranged to carry the fluid from said latter member to the applying member.
2. In a machine for applying fluid to a shoe part, an applying roll rotatable about

an inclined axis having a lowermost face exposed for the application of work thereto, a fluid receptacle, means for taking up fluid from said receptacle and delivering it to a point upon said applying roll remote from the point of application of the work, said means comprising a member dipping in the fluid in the receptacle, a transfer member positioned above the fluid in the receptacle and arranged to carry the fluid from said latter member to the applying member, and screw means for adjustably determining the amount of fluid delivered to the applying member by controlling the relative approach of two of said fluid-carrying members.

3. In a machine for applying fluid to a shoe part, a driven applying device, means for supporting said applying device for a movement of translation with respect to said machine, a fluid receptacle, means for taking up fluid from said receptacle and delivering it to said applying means, and an adjustable screw means for determining the relative positions of said applying roll and said supplying means when in fluid transferring relation, thereby to control the quantity of fluid applied.

4. In a machine for applying fluid, a frame, a slide carried by said frame, an applying roll carried by said slide, a fluid receptacle, means for picking up fluid from said receptacle and delivering it to said applying roll, adjustable means for determining one limit of movement of said slide, and resilient means urging said slide against said limiting device.

5. In a machine for applying fluid, a frame, a slide carried by said frame, an applying roll carried by said slide, a fluid receptacle, means for picking up fluid from said receptacle and delivering it to said applying roll, resilient means urging said slide in one direction, and operator-controlled means for moving said slide against said resilient means to effect the delivery of fluid to the applying member.

6. In a machine for applying fluid, a frame, a fluid receptacle, power-driven means for raising fluid from said receptacle, a slide mounted on said frame, an applying roll rotatably mounted on said slide, a transfer roll carried by said slide arranged to deliver fluid to the applying roll and to be moved into and out of co-operative relation to said power-driven fluid-delivering means, and means for controlling the amount of fluid delivered to said transfer roll by controlling the position of said slide.

7. In a machine for applying fluid, a frame, a fluid receptacle, power-driven means for raising fluid from said receptacle, a slide mounted on said frame, an applying roll rotatably mounted on said slide, a transfer roll carried by said slide arranged to deliver fluid to the applying roll and to be

moved into and out of co-operative relation to said power-driven fluid-delivering means, and adjustable means for determining one limit of movement of said slide.

8. In a machine for applying fluid, a frame, a fluid receptacle, power-driven means for raising fluid from said receptacle, a slide mounted on said frame, an applying roll rotatably mounted on said slide, a transfer roll carried by said slide arranged to deliver fluid to the applying roll and to be moved into and out of co-operative relation to said power-driven fluid-delivering means, adjustable means for determining one limit of movement of said slide, and resilient means urging said slide to its limiting position.

9. In a machine for applying fluid, a frame, a fluid receptacle, power-driven means for raising fluid from said receptacle, a slide mounted on said frame, an applying roll rotatably mounted on said slide, a transfer roll carried by said slide arranged to deliver fluid to the applying roll and to be moved into and out of co-operative relation to said power-driven fluid-delivering means, adjustable means for determining one limit of movement of said slide, resilient means urging said slide to its limiting position, and operator-controlled means for moving said slide against the opposition of said resilient means.

10. In a machine for applying fluid to a shoe part, a frusto-conical applying device mounted for rotation about an inclined axis so that its lowermost face is exposed for the application of work thereto, a cylindrical transfer roll mounted for co-operation with an upper point of said applying device, a fluid receptacle disposed to the rear of said applying device, and means for elevating fluid from said receptacle and delivering it to said cylindrical roll.

11. In a machine for applying fluid to a shoe part, a frusto-conical applying device mounted for rotation about an inclined axis so that its lowermost face is exposed for the application of work thereto, a cylindrical transfer roll mounted for co-operation with an upper point of said applying device, a fluid receptacle disposed to the rear of said applying device, means for elevating fluid from said receptacle and delivering it to said cylindrical roll, and means for adjustably controlling the relative positions of said cylindrical roll and said fluid applying device.

12. In a machine for applying fluid to a shoe part, a frusto-conical applying device mounted for rotation about an inclined axis so that its lowermost face is exposed for the application of work thereto, a cylindrical transfer roll mounted for co-operation with an upper point of said applying device, a fluid receptacle disposed to the rear of said applying device, and a frusto-conical fluid-delivering roll dipping in the fluid of said

- receptacle and co-operating with the face of said cylindrical roll.
13. In a machine for applying fluid to a shoe part, a frusto-conical applying device mounted for rotation about an inclined axis so that its lowermost face is exposed for the application of work thereto, a cylindrical transfer roll mounted for co-operation with an upper point of said applying device, a fluid receptacle disposed to the rear of said applying device, a frusto-conical fluid-delivering roll dipping in the fluid of said receptacle and co-operating with one face of said cylindrical roll, and means for controlling the separation between said cylindrical roll and either of said frusto-conical rolls. 6 70
14. In a cementing machine for the parts of boots and shoes, a rotatable fluid-applying member disposed at the front of the machine and having its lower face exposed for the application of work thereto, a fluid receptacle disposed at the rear of said applying member and extending below it, a fluid-supplying means dipping in said receptacle, and a substantially horizontally movable transfer means taking the fluid from the supplying means and delivering it to an upper part of the applying member whereby the receptacle is disposed at a substantial distance from the applying member and space is provided for the manipulation of work in contact with the applying member. 20 75
15. In a cementing machine for the parts of boots and shoes, a frusto-conical fluid-applying roll disposed at the front of the machine with its lowermost face exposed for the application of work thereto and having its axis inclined downwardly toward the rear, a fluid receptacle disposed at the rear of the applying roll, a fluid-supplying roll dipping in said receptacle arranged to take fluid therefrom, and a transfer roll mounted for rotation about said receptacle upon an upright axis, said transfer roll being interposed between the applying roll and the supplying roll and constructed and arranged to take fluid from the supplying roll and deliver it to the applying roll. 30 80
16. In a machine for applying fluid to a shoe part, an applying roll disposed at the front of the machine with its lower face exposed for the application of the shoe part thereto, and means for supplying fluid to said applying roll constructed and arranged to provide space for the manipulation of said shoe part in a substantially horizontal area extending to the rear from the applying roll, said means comprising a fluid receptacle disposed at a substantial distance to one side of the applying roll, means for elevating fluid from said receptacle, and a transfer means interposed between the applying roll and the receptacle constructed and arranged to receive fluid from the elevating means and to deliver it to the applying roll, said transfer 40 85
- means being disposed above the area provided for the manipulation of the work and out of the range of movement out of work. 15
17. In a machine for applying fluid to a shoe part, a fluid receptacle, a transfer roll mounted for rotation above said receptacle upon a vertical axis, a frusto-conical applying roll disposed in front of said transfer roll and having its axis inclined downwardly toward the rear, and a frusto-conical fluid-supplying roll dipping in said receptacle and arranged to co-operate with said transfer roll, said supplying roll being rotatable about an axis inclined downwardly toward the front of the machine. 90 95
18. In a machine for applying fluid to a shoe part, a cylindrical transfer roll mounted upon a substantially vertical axis, and frusto-conical fluid-applying and fluid-supplying devices co-operating with opposite faces of said transfer roll. 25 100
19. In a machine for applying fluid to a shoe part, a cylindrical transfer roll mounted upon a substantially vertical axis, frusto-conical fluid-applying and fluid-supplying devices co-operating with opposite faces of said transfer roll, and means for adjustably determining the separation of said transfer roll and either of said devices to control the quantity of cement applied. 30 105
20. In a machine for applying fluid to a shoe part, a fluid-applying roll, a fluid-transfer roll co-operating with said applying roll, a slideable bearing for one of said rolls, driving connections between said rolls constructed and arranged to permit relative adjustment thereof without impairing the driving connection, and means for adjusting the separation between said rolls to control the quantity of cement applied comprising means adjusting said slideable bearing. 40 110
21. In a machine for applying fluid, a frusto-conical applying roll disposed upon an inclined axis at the front of the machine, a fluid receptacle disposed toward the rear of the machine, fluid-supplying means dipping in said receptacle and arranged to elevate fluid therefrom, a transfer means interposed between said applying roll and said fluid-supplying means, and a lip upon said receptacle extending beneath said transfer means arranged to underlie the point of co-operation between said transfer means and said supplying means. 45 115
22. In a machine for applying fluid, a frusto-conical applying roll disposed upon an inclined axis at the front of the machine, a fluid receptacle disposed toward the rear of the machine, fluid-supplying means dipping in said receptacle and arranged to elevate fluid therefrom, a transfer means interposed between said applying roll and said fluid-supplying means, and a lip upon said receptacle extending beneath said transfer means arranged to underlie the point of co- 50 120
- 60 125
- 65 130

operation between said transfer means and said applying roll.

23. In a machine for applying fluid, a frusto-conical applying roll disposed upon an inclined axis at the front of the machine, a fluid receptacle disposed toward the rear of the machine, fluid-supplying means dipping in said receptacle and arranged to elevate fluid therefrom, a transfer means interposed between said applying roll and said fluid-supplying means, and a lip upon said receptacle extending beneath said transfer means arranged to underlie the point of co-operation between said transfer means and said applying roll and also to underlie the point of cooperation between said transfer means and said supplying means.

24. In a machine for applying fluid, a frusto-conical rotatable fluid-applying means disposed upon an inclined axis at the front of the machine, a fluid receptacle disposed toward the rear of the machine to take it out of the range of movement of work manipulated in contact with the applying means, means for lifting fluid from said receptacle and delivering it to said applying means, and a work support extending outwardly from said fluid receptacle into co-operative relation with said applying means.

30 In testimony whereof I have signed my name to this specification.

MARY E. ERICKSON,
Executrix of the Will of Edward Erickson.
